MANUALLY ACTUATED CABLE HOIST

Roy Mallory, Coquille, Oreg.

Application February 6, 1951, Serial No. 209,600

5 Claims. (Cl. 254—135)

1

This invention relates to hand lever actuated hoisting devices particularly adapted for carrying heavy objects up vertically disposed cables such as power shovel cables, and in particular a hoist positioned on a cable, with a lever pivotally mounted intermediate of the ends thereof and with oppositely disposed gripping jaws mounted in the ends and positioned to grip the cable, and with means for actuating the gripping jaws by the lever whereby as the hand lever is forced downwardly the hoist moves upwardly on the cable and as the hand lever is moved upwardly the upper jaw holds the device on the cable as the lower jaw is drawn upwardly.

The purpose of this invention is to provide means for hoisting or elevating heavy objects such as tools and the like upwardly on the cables particularly of steam shovels, power shovels and the like.

Various types of hoisting devices have been used for different purposes and different combinations of ratchets have been used for conveying travelers particularly on horizontally disposed tracks, however, such devices are not adapted for carrying tools and other heavy objects up cables particularly of power shovels and the like. With this thought in mind this invention contemplates a traveler formed to be positioned upon a cable with gripping jaws in the ends and with a lever pivotally mounted between the ends for actuating the gripping jaws and traveler whereby as the lever is actuated the traveler moves upwardly on the cable.

The object of this invention is, therefore, to provide means for forming a hoist whereby upon operation of a hand lever pivotally mounted thereon the hoist crawls upwardly on a cable for carrying tools and the like thereon.

Another object of the invention is to provide a manually actuated hoist for carrying tools and the like up cables that may be used without changing the cable or without permanently attaching parts thereto.

A further object of the invention is to provide a manually actuated elevating device for carrying objects upwardly on cables and the like which is of a simple and economical construction.

With these and other objects and advantages in view the invention embodies a casing substantially U-shaped in cross section with oppositely disposed gripping jaws pivotally mounted in the ends of the casing, a traveling carriage on which one of said jaws is mounted, a hand lever pivotally mounted on the casing and positioned at a point intermediate of the ends thereof, means

2

connecting the hand lever to the carriage in which one of the gripping jaws is pivotally mounted and means actuating the gripping jaws by the hand lever for alternately gripping the cable.

Other features and advantages of the invention will appear from the following description taken in connection with the drawings wherein:

10 Figure 1 is a side elevational view showing the improved hoisting device with part of the hand lever broken away.

15 Figure 2 is a vertical longitudinal section through the device with the hand lever shown in the lower position.

15 Figure 3 is a front elevational view of the hoisting device.

Figure 4 is a detail illustrating a clevis at the lower end of the device to which tools and other objects may be attached.

20 Figure 5 is a detail showing an end elevational view of a slider carried by one of the gripping jaw mounting elements.

Figure 6 is a plan view of the slider shown in Fig. 5.

25 Figure 7 is a plan or end elevational view of the upper gripping jaw mounting elements with the slider normally positioned on the outer end thereof, and other parts omitted.

Figure 8 is an end elevational view showing one of the cable gripping jaws.

30 Figure 9 is an end elevational view showing the sliding carriage in which the lower gripping jaw is pivotally mounted.

Figure 10 is a detail showing a plan view of the inner end of the hand lever and with the hoist casing and other parts omitted.

Referring now to the drawings wherein like reference characters denote corresponding parts the improved cable hoist of this invention includes an elongated casing or shoe 10, U-shape in

40 cross section, a hand lever 11, pivotally mounted on the shoe through arms 12 and 13 with a pin 14, an upper gripping jaw 15, a lower gripping jaw 16, a sliding carriage 17 in which the gripping jaw 16 is pivotally mounted by a pin 18, a rocker arm 19, positioned on a pin 20 by which the gripping jaw 15 is pivotally mounted, and connecting rods 21 and 22 for connecting the gripping jaw actuating elements to a control shaft 23 which extends through the hand lever 11.

45 The shoe 10 extends continuously from a point 24 at the upper end to a point 25 forming the lower end and the intermediate portion is provided with an enlarged section 26 through which the pin or bolt 14 extends. The lower end of the

50 55

shoe is provided with a clevis 27 by which tools and other objects or devices are suspended from the shoe.

The upper end of the shoe is provided with a U-shape yoke having parallel arms 28 and 29 at the outer ends and the arms are provided with flanges 30 and 31, respectively.

The upper gripping jaw 15 is provided with an inner arcuate end in which the gripping teeth are positioned. The teeth of the jaw 15, which are indicated by the numeral 32 are positioned to grip a cable 33 as the cable moves upwardly through the shoe and as the shoe moves upwardly on the cable the teeth are held downwardly by the hand lever 11, as illustrated in Fig. 2. The hand lever is connected to the jaw 15 by the rod 21 which extends through an opening 34 in an end 35 of the shaft 23, and the upper end of the rod 21 is connected to the inner end of the rocker arm 19, the end 36 of the rod extending through an opening 37 in the rocker arm, and being held in the rocker arm by a cotter pin 38. The rod 21 is provided with clamps 39 and 40 that provide stops, being positioned on opposite sides of the end 35 of the shaft, and the clamps are provided with screws 41 and 42, respectively, as shown in Fig. 3.

The gripping jaw 15 is resiliently held upwardly by a spring 43, the upper end of which is held on a pin 44 on the under side of the jaw and the lower end of which is held in a split hanger formed with arcuate sections 45 and 46. A head 47 having a pin 48 on the upper end for holding the end of the spring is secured between the sections 45 and 46 with a pin 49.

The outer end of the rocker arm 19 is pivotally connected to a slider 50 which, as shown in Figs. 5 and 6 is provided with flanges 51 and 52 that extend around flanges 30 and 31 on the yoke formed with the side plates 28 and 29. The slider is provided with an arm 53 having a socket 54 in the lower end and a link 55 connects the rocker arm to the slider with the lower end 56 thereof held in the socket 54 by a cotter pin 57 with the upper end 58 held in an opening 59 in the end of the rocker arm by a cotter pin 60. The slider 50 is provided with an opening 61 through which the outer end of the jaw 15 extends, as illustrated in Fig. 2 and as the inner end of the rocker arm is drawn downwardly by the hand lever 11 the outer end moves upwardly drawing the slider 50 upwardly through the link 55, and thereby moving the outer end of the jaw 15 upwardly. As illustrated in Fig. 2 the lower edge of the jaw 15 engages the upper end of the arm 53 so that as the slider moves upwardly it forces the outer end of the gripping jaw upwardly as the opposite or gripping end thereof moves downwardly so that the teeth 32 move away from the cable 33. By the same means as the hand lever 11 is moved upwardly the inner end of the rocker arm moves upwardly with the outer end moving downwardly, whereby the inner end of the gripping jaw is free to be urged upwardly by the spring 43. Upon upward movement of the hand lever 11 the upper end of the shoe 10 grips the cable and the carriage 17, which carries the lower jaw 16 is drawn upwardly to take another bite.

The carriage 17 is slidably mounted in the shoe 10 and this is also U-shape in cross section having flanges 62 and 63 on the outer edges upon which a slider, similar to the slider 50, is positioned. The socket 54 of the lower slider is connected by the rod 22 to the shaft 23 with the rod

passing through an opening 64 in an end 65 of the shaft, and the rod 22 is also provided with clamps 66 and 67 that are adjustably mounted on the rod by screws 68 and 69. The lower end 70 of the rod 22 is secured in the socket 54 of the slider by a cotter pin 71.

The lower gripping jaw 16, which is provided with teeth 72 is pivotally mounted in the carriage 17 by a pin 18 and the lower edge is provided with a notch 73 that is positioned to receive the upper end of the arm 53 of the slider 50. The lower edge of the jaw 16 is also provided with a pin 74 over which the upper end of a spring 75 is positioned and the lower end of the spring is held by a head 76 having a pin 77 on the upper end in a split hanger having substantially semi-circular sections 78 and 79, which extends downwardly from the lower end of the carriage, and in which the head 76 is secured by a pin 80. The lower end of the shoe 10 is provided with a cotter pin 81 that extends through the sides thereof, as shown in Fig. 3 to limit downward movement of the carriage 17.

The upper end of the carriage 17 is provided with extensions 82 and the extensions are secured to the hand lever 11 by links 83, the lower ends of which are attached to the extensions 82 of the carriage by a bolt 84 and the upper ends of which are secured between the arms 12 and 13 of the hand lever by a bolt 85.

It will be noted that as the hand lever 11 is moved downwardly, to the position shown in Fig. 2, the rod 22 actuates the slider 50 whereby the outer end of the gripping jaw 16 is moved downwardly with the opposite or inner end moving upwardly so that the jaw grips the cable, and with the jaw gripping the cable, the bolt 85 forms a pivot point with the bolt or pin 14 moving upwardly so that the shoe 10 is carried upwardly on the cable.

As the hand lever 11 reaches the limit of the downward movement and starts upwardly the gripping jaw 15 is actuated into gripping relation with the cable to hold the shoe in the upper position and the gripping jaw 16 is released from the cable so that the carriage 17 moves upwardly in the shoe.

The shaft 23 which actuates the rods 21 and 22 extends through elongated slots 86 and 87 in the arms 12 and 13, respectively of the hand lever and the intermediate part of the shaft is connected by a bar 88 to a U-shape lever 89 at the outer end of the tubular section of the handle whereby a cam surface 90 of the lever 89 rides on the end of the handle and as the lever 89 is drawn outwardly to a horizontal position the shaft 23 moves to the outer ends of the slots thereby changing the positions of the rods 21 and 22 so that the movement of the gripping jaws may be reversed to reverse the direction of the travel of the shoe or hoist on the cable. A spring 91 is provided on the bar 88 to return the shaft 23 when the lever 89 is turned downwardly to the position shown in Fig. 1 and the end of the bar 88 is mounted in the sides of the lever 89 by a split pin 92.

With the parts as shown in Figure 2, the gripping jaws 15 and 16 are actuated by the lever 11 whereby the upper jaw 15 grips the cable and holds the device in position as the carriage 17 in which the lower jaw 16 is mounted is drawn upwardly with upward movement of the lever 11; whereas to lower the device on the cable the shaft 23 is drawn outwardly to the outer ends of the slots 86 and 87 by the lever 89 with the re-

sult that the rod 21 through the rocker arm 19 raises the upper slider 50 and rod 22 moves the lower slider 50 downwardly.

In the position of moving the hoist upwardly the pin 23 and the ends or pins 36 and 70 of the rods 21 and 22 are, substantially, in a straight line whereas with the pin 23 drawn outwardly to the outer ends of the slots 86 and 87 the three points form a triangle whereby, as illustrated in Figure 2, the inner end of the rocker arm 19 is drawn downwardly with the pin 23 moved to the outer ends of the slots 86 and 87.

Moving the inner end of the rocker arm 19 downwardly from the position shown in Figure 2, moves the outer end of the jaw 15 upwardly thereby moving the opposite end of the jaw downwardly, and with the shorter radius from the teeth 32 to the pin 20 at the upper side of the jaw, the jaw is released from the cable, whereby with the conditions reversed in relation to the jaw 16 the jaw 16 grips the cable permitting the shoe to slide downwardly by the weight of a tool or the like on the clevis 27. With upward movement of the lever 11 the jaw 15 will again grip the cable permitting the carriage 17 with the jaw 16 to slide downwardly to grip the cable at lower point.

With the parts arranged in this manner a cable, as indicated by the numeral 33 is inserted through the shoe, as illustrated in Fig. 2 and with a tool or other object carried by the clevis 27 the hand lever 11 is moved downwardly forcing the gripping jaw 16 into engagement with the cable, as shown in Fig. 2 and at the same time forcing the shoe upwardly on the cable with the pin 14 moving upwardly from the pin 85 which provides the fulcrum. In this movement the carriage 17 remains stationary on the cable with the shoe sliding upwardly over the carriage. As the lever 11 reaches the limit of its downward movement the action is reversed with the lever 11 moving upwardly whereby the gripping jaw 15 is actuated into gripping relation with the cable. The gripping jaw 15 holds the shoe on the cable so that the pin 85 moves upwardly drawing the carriage 17, the carriage sliding upwardly through the shoe. At the end of the upward movement of the lever 11 the action is reversed as the lever 11 moves downwardly the gripping jaw 16 takes another bite and forces the shoe with the weight or tool suspended therefrom upwardly on the cable.

Downward movement of the carriage 17 in the shoe is limited by the pin 81 and to hold the carriage in alignment in the shoe the lower end is provided with an extended sleeve 93 the inner side of which is provided with a split 94 and a similar sleeve 95 with a split 96 therein extends upwardly from the upper end of the yoke 28.

It will be understood that modifications may be made in the design and arrangement of the parts without departing from the spirit of the invention.

What is claimed is:

1. A cable hoist comprising a cable, an elongated shoe, U-shape in cross section positioned on the cable, a gripping jaw pivotally mounted in the shoe, spaced from the upper end thereof and positioned to grip the cable, a carriage also U-shape in cross section slidably mounted in the lower part of the shoe, a gripping jaw pivotally mounted in the carriage and positioned to grip the cable, a hand lever pivotally mounted on the shoe and positioned between the said gripping jaws, means connecting the gripping jaws to the

lever whereby upon reciprocation of the lever the shoe travels on the cable, and means reversing the position of the gripping jaws to reverse the direction of travel of the hoist on the cable.

5. In a cable carrier, the combination which comprises a cable, an elongated shoe, U-shape in cross section positioned on the cable, a yoke, U-shape in cross section, mounted in the upper end of the shoe, a carriage also U-shape in cross section slidably mounted in the lower part of the shoe, capable gripping jaws pivotally mounted in the yoke and carriage, sliders mounted on the yoke and carriage and positioned to actuate the gripping jaws, a hand lever pivotally mounted on the shoe and positioned between the yoke and carriage, a link connecting the lever to the carriage, and means actuating the sliders by the lever.

10. In a cable hoist, the combination which comprises an elongated shoe, U-shape in cross section, a cable extended through the shoe, a yoke, also U-shape in cross section mounted in the upper end of the shoe, a carriage, also U-shape in cross section slidably mounted in the lower part of the shoe, gripping jaws pivotally mounted in the yoke and carriage, respectively, sliders slidably mounted on extended ends of the yoke and carriage and having slots therein through which outer ends of the gripping jaws extend, a lever mounted on the shoe and positioned between the yoke and carriage, links pivotally connecting the lever to the carriage, a shaft transversely positioned in the lever and slidably mounted therein, means actuating the shaft from the outer end of the lever, and means pivotally connecting the shaft slidably mounted in the lever to the gripping jaws for actuating the jaws to alternately grip the cable.

15. In a cable hoist, the combination which comprises an elongated shoe, U-shape in cross section and having a clevis carried by the lower end, a yoke U-shape in cross section mounted in the upper end of the shoe, a carriage also U-shape in cross section slidably mounted in the lower part of the shoe, transversely disposed shafts

20 pivotally mounted in the yoke and carriage, respectively, cable gripping jaws pivotally mounted through the said shafts of the yoke and carriage, springs positioned in the yoke and carriage for urging the inner ends of the cable gripping jaws upwardly, sliders having openings therethrough mounted on extended ends of the said yoke and carriage, respectively, a rocker arm mounted on the shaft positioned in the yoke, means pivotally connecting an extended end of the rocker arm to the slider slidably mounted on the yoke, a hand lever pivotally mounted on the shoe and positioned between the yoke and carriage, a shaft

25 slidably mounted in the lever and having ends extended from the sides thereof, a bar connecting one end of the shaft to the inner end of the said rocker arm, a bar connecting the opposite end of the shaft with the slider slidably mounted on the carriage, links connecting the lever to the carriage, and means actuating the shaft extended through the lever from the outer end of the lever.

30. In a cable hoist, the combination which comprises an elongated shoe, U-shape in cross section and having a clevis carried by the lower end, a yoke U-shape in cross section mounted in the upper end of the shoe, a carriage also U-shape in cross section slidably mounted in the lower part of the shoe, transversely disposed

75

shafts pivotally mounted in the yoke and carriage, respectively, cable gripping jaws pivotally mounted through the said shafts of the yoke and carriage, springs positioned in the yoke and carriage for urging the inner ends of the cable gripping jaws upwardly, sliders having openings therethrough through which the gripping jaws extend slidably mounted on extended ends of the said yoke and carriage, a rocker arm mounted on the shaft positioned in the yoke, means pivotally connecting an extended end of the rocker arm to the slider slidably mounted on the yoke, a hand lever pivotally mounted on the shoe and positioned between the yoke and carriage, a shaft slidably mounted in the lever and having ends extended from the sides thereof, a bar connecting one end of the shaft to the inner end of the said rocker arm, a bar connecting the opposite end of the shaft with the slider slidably mounted

on the carriage, links connecting the lever to the carriage, means actuating the shaft extended through the lever from the outer end of the lever, and stops adjustably mounted on the rods connecting the extended ends of the shaft to the rocker arm and slider, respectively, and positioned on opposite sides of the extended ends of the shaft for adjusting the movement of the gripping jaws.
